UNITED STATES PATENT OFFICE.

RUDOLF HAUPTNER, OF BERLIN, GERMANY.

VETERINARY INSTRUMENT FOR EMBRYOTOMY.

Application filed April 13, 1927, Serial No. 183,482, and in Germany April 15, 1926.

This invention relates to a veterinary instrument for use in the case of difficult births and intended to destroy the foetus, but to save the female animal.

5 There has been done up to now in cases of the kind in question a certain preliminary work consisting in introducing a centre-bit with a guiding pointed end for crushing and disintegrating the spine and its 10 surrounding parts corresponding with the progress of the bit in the spine channel. That is, however, a tedious work which requires much time and can be successful only as far as that crushing and disintegrating is concerned, whereas the removing of more bulky 15 body masses in order to decrease the size of the foetus cannot be effected with an instrument of the kind stated.

But that can now be done by means of the 20 improved instrument or device constituting the subject-matter of this invention. It consists of a saw tube, that is to say, a tube of suitable length and diameter, one end of which has saw-teeth, whereas the other end 25 has laterally extending grips by which it can be turned. The saw end of the tube may, besides, be provided with a turnable, as well as shiftable protective tube, or piece of tube, by which the saw teeth can be covered, if de- 30 sired or necessary, that is to say, if there arises a certain danger that the walls of the sheath or theca of the female animal could be hurt by the teeth when the device is applied.

35 The invention comprises also special auxiliary means or additional devices and implements formed by drill-like spindles and harpoon-like members arranged within the saw tube and serving as guides, as well as 40 abutments, as more fully described herein-after. One of the additional devices consists of a guide spindle provided at its front end with a knife that can be unclasped and serves for cutting off, and conveying out of 45 the body of the female animal, masses located around the spine.

The invention is illustrated diagrammatically and by way of example on the accompanying drawings, on which Figure 1 is 50 partly a side-view of, and partly a section through a saw-tube designed according to this invention, together with a harpoon-like member arranged within that tube; Figure 2 is a separate view of the front end of the 55 saw-tube, drawn to a greatly enlarged scale, together with the correspondingly enlarged

end of the so-called harpoon, this latter being turned 90° with respect to Fig. 1; Figure 3 shows the front end of an ordinary screw-bit intended as a substitute for the harpoon 60 (in certain cases); Figure 4 shows a modification of the parts shown in Fig. 1; Figure 5 is a view similar to Fig. 2, but showing a modification, viz, the same as in Fig. 4 and Figure 6 is a frontal view of the parts 65 shown in Fig. 5.

The instrument consists of the tube *a*, one 70 end of which is provided with saw-teeth *a'*. This end of the tube is, preferably, reduced a little in diameter, as shown in Fig. 2, in order to allow of easier insertion into the body of the female animal. When the tube has been inserted to a sufficient depth, it can be turned by means of grips *b* provided at 75 its outer end, and it is, thus, possible to make a circular cut which penetrates deeper and deeper in proportion to the axial shifting forward of the tube during the sawing, the cut-off portions being received within the tube.

80 In order to provide for a guide for the tube, as well as for a means for holding it securely during the sawing operation, a centrally or axially located spindle is provided for instance of the form shown in Fig. 3, in 85 which the spindle forms a kind of bit or screw-bit *r* which is turned or screwed into the foetus prior to applying the saw-tube.

Instead of the simple screw-bit *r* (Fig. 3), a harpoon-like implement *h* *h'* (Figs. 1 and 90 2) may be employed. The outwardly projecting end of the shaft *h* of the harpoon is provided with a grip *g* and with an eye *o*. The grip is attachable and detachable. The eye *o* serves for attaching a strong cord or 95 thin rope to the harpoon. The shaft *h* is guided within the tube *a* by a guide-tube *d* that is firmly connected with two disks *f* *f*. The united parts *f* *d* *f* can be shifted within the tube, and give way in proportion to the 100 progress of the cutting, i. e. in proportion to the cut-off mass entering more and more into the tube.

The harpoon shaft is crooked at *h'* and forms at its end an arrow-head *i*, the rearwardly directed leg of which is designed as a barb *j* (Fig. 2).

In order to give a practical example, it may be supposed that in a given case a foetus of too large size lies with its rear at the 110 sheath or theca of the female animal. When those parts of the skin and the muscles of

the foetus that are in the way have been cut through, the harpoon h h' i j is pushed into the rear of the foetus in such a position that the barb j is directed toward the abdomen 5 of the animal. When the head of the harpoon has arrived in the abdominal cavity, the harpoon is turned for 180° so that the barb is directed upwardly. Now the harpoon is withdrawn so that the barb j engages 10 the rim of the share bone or pubic bone or the front rim of the ilium in front of the joint-socket or elsewhere at the basin or pelvis. All this having been effected, the tube a is shoved forward upon the disks f f 15 until its teeth a^1 contact with the foetus. The end of the shaft h is connected with a strong cord or thin rope. Now the tube a is turned by means of the grips b , and the cord or rope is put under tension, when the toothed 20 end of the tube will penetrate into the foetus, and the parts severed off in this way will enter into the tube, more and more, down to about 20 cm. depth. These parts can then be drawn out of the foetus and, thus also 25 out of the body of the female animal.

The combination of the toothed tube with the harpoon is suited to the purpose also in other cases in which it is necessary to provide guide means for the toothed tube and 30 keep these means themselves in proper direction.

Instead of only one barb, two or more may be attached to the end i of the crooked portion h^1 of the harpoon shaft h .

35 In the modification shown in Figs. 4-6, the front-end of the saw-tube is provided with a sleeve e that can be turned, as well as shifted, on the tube, and the object of which is to cover the saw-teeth a^1 in order 40 to render them inactive in certain cases for a certain time, and to prevent thereby the female animal from being damaged. The sleeve e is provided with an oblique guide slot u engaged by a pin v projecting forth 45 from the tube a . The pin can enter the slot u through a passage u^1 . When the working end of the tube a has been carefully introduced into the animal and is then turned a little in counter-clockwise direction, the 50 sleeve e does not take a part in this turning but is retained in its former position, in consequence whereof the sleeve is shifted axially upon the tube corresponding to the obliquity of the slot u , its position relatively 55 to the tube being then that shown in dotted lines in Fig. 5, in which position it covers the teeth a^1 of the tube. When then the tube is turned in the reverse direction in which its teeth could otherwise become active, the sleeve e is withdrawn from the teeth and now these can effect the sawing.

60 The guide-spindle s , Fig. 4, consists of a straight steel rod provided at its rear end with a grip g , as well as with an eye o , and fitting into the spine channel of the foetus.

The front end which is the end to be introduced into said channel is tapered, and there-behind is a hinge c on which a knife m having a barbed end n can be turned. This device is used when the spine of the foetus is 70 to be drawn out together with the body masses adhering to it. The rod s is inserted into the spine channel of the foetus either from the rear end of the same or, may be, from the head of the same, and only then 75 the saw-tube is applied. The proper position of the saw tube is secured by the rod s .

The knife m does not form an obstacle to inserting the rod s into the spine channel, because its position is then that shown in 80 dotted lines in Fig. 5. When the rod s is withdrawn the barbed end n of the knife m forms an obstacle, in consequence whereof the knife is erected into the position shown in full lines in Fig. 5. Thereafter the grip 85 g is removed from the rod s and now the saw-tube a is rotated by means of its grip b , it being understood that the sleeve e was in the position shown in dotted lines in Fig. 5 90 when the instrument was applied to the female animal. When then the tube a is turned in clockwise direction, the sawing procedure commences, as already described with respect to Figs. 1 and 2. Also the bony projections extending forth laterally 95 from the spine are sawed off. The body portions of the foetus that have been received in the tube a are finally severed off completely by the knife m , in that this is turned by means of the rod s , the grip g being again 100 secured to the rod for that purpose.

As the rod s with the knife m may be used in connection with several tubes having different diameters, it is suited to the purpose to make the knife m exchangeable, 105 and provide for a corresponding plurality of knives so that always the proper knife can be employed in connection with a tube of larger or smaller diameter.

I claim:

1. A veterinary embryotomic instrument, 110 comprising, in combination, a tube having saw-teeth at one end, a sleeve shiftable relative to the toothed end for controlling the activity of the toothed end, and means adapted to effect the shifting of said sleeve automatically.

2. A veterinary embryotomic instrument, 115 comprising, in combination, a tube having saw-teeth at one end, means for turning said tube, a spindle-forming rod extending lengthwise through the toothed tube, means by which said rod and the tube guide one another, a barbed implement at that end of the said rod which lies in front of the 120 toothed end of the said tube, and means for turning this latter, substantially and for the purpose set forth.

3. A veterinary embryotomic instrument, 125 comprising, in combination, a tube having 130

- saw-teeth at one end, means for turning said tube, a spindle-forming rod extending lengthwise through the toothed tube, means by which said rod and the tube guide one another, a blade-like barbed implement at that end of the said rod which lies in front of the toothed end of the said tube, and means for turning this latter, substantially and for the purpose set forth.
- 5 4. A veterinary embryotomic instrument, comprising, in combination, a tube having saw-teeth at one end, means for turning said tube, a spindle-forming rod extending lengthwise through the toothed tube, means by which said rod and the tube guide one another, a rearwardly directed blade-like barbed implement at that end of the said rod which lies in front of the toothed end
- 10 of the said tube, and means for turning this latter, substantially and for the purpose set forth.
- 15 5. A veterinary embryotomic instrument, comprising, in combination, a tube having saw-teeth at one end, means for turning said tube, a spindle-forming rod extending lengthwise through the toothed tube, means by which said rod and the tube guide one another, a barbed knife-blade hinged to the said rod and extending in the direction to the toothed end of the tube and being adapted to be erected so as to stand about at right angles with respect to the rod, and means for turning the tube, substantially and for the purpose set forth.

In testimony whereof I affix my signature.

RUDOLF HAUPTNER.
